United States Patent Office

Des. 185,868

Patented Aug. 11, 1959

185,868

COMBINED CHAIR AND DESK

Alfred C. Hoven, William S. Lindberg, and Walter E. Nordmark, Grand Rapids, Mich., assignors to American Seating Company, Grand Rapids, Mich., a corporation of New Jersey

Application June 23, 1958, Serial No. 51,481

Term of patent 14 years

(Cl. D33—11)

Fig. 1

Des. 185,868

PAGE 2

Fig. 2

Fig. 3

Figure 1 is a front and side perspective view of a combined chair and desk showing our new design, the cover for the desk box being here shown in an elevated, inclined position for reading and writing;

Figure 2 is a rear and side perspective view of the same with the cover for the desk box in closed position; and Figure 3 is a sectional view on line 3—3 of Figure 2. We claim:

The ornamental design for a combined chair and desk, substantially as shown and described.
